US00D962446S

(12) **United States Design Patent** (10) **Patent No.:** **US D962,446 S**
Bernstein et al. (45) **Date of Patent:** **** Aug. 30, 2022**

(54) **ANALYTE SENSOR DEVICE**

(71) **Applicant:** **ABBOTT DIABETES CARE INC.**,
Alameda, CA (US)

(72) **Inventors:** **Daniel Milfred Bernstein**, El Granada, CA (US); **Martin J. Fennell**, Concord, CA (US); **Mark Kent Sloan**, Redwood City, CA (US); **Lei He**, Moraga, CA (US); **Gary Alan Hayter**, Oakland, CA (US); **Namvar Kiaie**, Danville, CA (US); **Jean-Pierre Cole**, Tracy, CA (US); **Marc Barry Taub**, Mountain View, CA (US)

(73) **Assignee:** **ABBOTT DIABETES CARE, INC.**,
Alameda, CA (US)

(**) **Term:** **15 Years**

(21) **Appl. No.:** **29/776,976**

(22) **Filed:** **Apr. 1, 2021**

Related U.S. Application Data

(63) Continuation of application No. 16/700,799, filed on Dec. 2, 2019, which is a continuation of application No. 14/841,224, filed on Aug. 31, 2015, now Pat. No. 10,492,685, which is a continuation of application No. 12/807,278, filed on Aug. 31, 2010, now Pat. No. 10,136,816.

(57) **CLAIM**

The ornamental design for an analyte sensor device, as shown and described.

DESCRIPTION

FIG. 1 is a perspective view of an analyte sensor device showing our new design; and, FIG. 2 is a top plan view thereof.

The dashed broken lines in the figures illustrate portions of the analyte sensor device that form no part of the claimed design.
